UNITED STATES PATENT OFFICE

2,441,266

TOBACCO PIPE

Everett E. Gregory, Kansas City, Mo.

Application October 22, 1945, Serial No. 623,641

2 Claims. (Cl. 131—184)

1

This invention relates to smoking pipes of the character wherein tobacco is packed, and the primary aim is the provision of unique tamping structure for the tobacco, which structure is removably associated with the bowl of the pipe and is provided with means for cleaning the end thereof when in the housed condition.

A further aim of this invention is to provide a tobacco pipe with a removable insert and which has yieldable means for retaining the insert in place, and a basin below the insert for the collection of the oil from the tobacco being burned.

Further aims of the invention include the provision of a tobacco pipe, having a specially housed tamper; means for scraping collected ash or the like from the end of the tamper; and a compartment formed in the pipe body for collecting the ash or the like as it is removed from the tamper end.

Other aims of the invention will appear during the course of the following specification, referring to the accompanying drawing, wherein:

Fig. 1 is a partial longitudinal central sectional view through the tobacco pipe made in accordance with the present invention.

Fig. 2 is a sectional view taken on line II—II of Fig. 1 with the tamper removed; and

Fig. 3 is a fragmentary longitudinal sectional view similar to Fig. 1, but showing the tamper in an operative position.

The pipe comprises a body portion 10 and a removable stem 12, both of which are generally well-known but the former, in this instance, is specially designed to have a removable insert 14 held in place by a resilient annular marginally split clip 16 which cooperates with a detent 18 integral with bowl 20 of body 10.

The illustrated insert 14 is made of metal, but in practice the material from which it is constructed may be wood or other substance best suitable for the production of satisfactory tobacco pipes.

An upward pull on clip 16 will release the inter-engagement between members 16 and 18 and allow the withdrawal of insert 14.

Insert 14 is shorter than bore 22 of bowl 20. The bottom portion of insert 14 is perforated as at 24 and it is through these perforations that the oil from the burning tobacco is drawn when the pipe is in use. A basin 26 collects the oil from the tobacco and prevents its movement along conduit 28 which is continued throughout the length of stem 12.

It is always desirable to tamp the tobacco, especially immediately after lighting a charge there-

of, because of the swelling due to combustion. It is common practice for a smoker to use the end of his finger, or some handy implement to tamp the tobacco into insert 14, but there are objectionable results arising from the use of a finger or some handy instrument, in that there is always some ash or dirt collected, and in most instances, burning will occur because glowing ash will be collected on the member employed for tamping. A tamper should be conveniently disposed within access of the user of the pipe and accordingly, such an instrument is removably held within a housing of body 10.

In the illustrated embodiment of the invention shown in Figs. 1, 2 and 3, tamper 30 is held in a socket 32 below bowl 20. A compartment 34 immediately below socket 32 is in communication therewith and at the zone of juncture between compartment 34 and socket 32 there is placed a brush 36 on removable plug 38. This brush is engaged by the end of tamper 30 when the parts are in the relation shown in Fig. 1, and if any ash has collected on the end of tamper 30, it will be removed merely by turning tamper 30 to polish the inner end thereof.

A grip 40 on the outer end of tamper 30 serves as a means for manipulating the tamper and as it is rotated about its axis, the ash brushed therefrom will fall into compartment 34. After a time, compartment 34 should be emptied and a plug 42 may then be removed from its threaded engagement with bowl 20 and all of the matter collected in compartment 34 emptied through the hole provided for the plug 42.

From the foregoing it will be apparent that a removably housed tamper may be placed in a socket formed in the pipe body 10 and a brush may be removably mounted on the body to clean one end of the tamper.

Tobacco pipes having physical characteristics far different from those illustrated and described, might be produced without departing from the spirit of the invention or scope of the appended claims.

Having thus described the invention, what is claimed as new and desired to be secured by Letters Patent is:

1. A smoking pipe comprising a body having a bowl and a stem; a socket formed in said body; a tamper removably housed in said socket; a brush removably mounted on the body in a place to clean one end of the tamper when the latter is in the housed position; and a compartment formed in the body below and in communication with the said socket for catching the substance

dislodged from the end of the tamper by the brush when the tamper is moved to clean the same.

2. A smoking pipe comprising a body having a bowl and a stem; a socket formed in said body; a tamper removably housed in said socket; a brush removably mounted on the body in a place to clean one end of the tamper when the latter is in the housed position; a compartment formed in the body below and in communication with the said socket for catching the substance dislodged from the end of the tamper by the brush when the tamper is moved to clean the same; and a discharge opening in the body having a removable plug therein for emptying the said compartment. 15
